UNITED STATES PATENT OFFICE.

PHILMORE F. SPERY, OF CHICAGO, ILLINOIS.

RADIATOR FOR MOTOR-DRIVEN VEHICLES.

1,325,215.

Specification of Letters Patent. Patented Dec. 16, 1919.

Application filed December 28, 1918. Serial No. 268,679.

To all whom it may concern:

Be it known that I, PHILMORE F. SPERY, a citizen of the United States, and a resident of the city of Chicago, in the county of Cook and State of Illinois, have invented a certain new and useful Improvement in Radiators for Motor-Driven Vehicles; and I do hereby declare that the following description of my said invention, taken in connection with the accompanying sheet of drawing, forms a full, clear, and exact specification, which will enable others skilled in the art to which it appertains to make and use the same.

My invention relates generally to improvements in radiators for motor driven vehicles; and it consists essentially, in the novel and peculiar combination of parts and details of construction, as hereinafter first fully set forth and described and then pointed out in the claims.

The object of my present invention is, the production of an efficient filler for the air conduits of radiators for motor vehicles, and the method of producing the same rapidly and economically. These fillers serve the purpose of heat conductors, *i. e.* to abstract heat from the walls of the water-tubes in these radiators, and at the same time afford means for reinforcing the cellular structure of the cores of these radiators and to prevent the water tubes from spreading under water pressure therein.

In order to accomplish these desirable objects, I construct the radiator core and the fillers therein, as illustrated in the drawings forming a part of this specification, in which—

Figure 1 is an end elevation of a fragment of a radiator core embodying my invention. Fig. 2 is a front elevation of the same. Fig. 3 is a sectional plan of a portion of the core, on line 3—3 of Fig. 1. Fig. 4 is a plan of a filler strip employed in this core and illustrating the first step in the production thereof. Fig. 5 is a similar view of the filler strip and showing the second step; and Fig. 6 is an edge view of the same. Fig. 7 is an edge view of the filler strip and showing the condition thereof after the third operation has been performed thereon. Fig. 8 is an elevation of the filler in its complete form as seen from the back thereof. Fig. 9 is an end view of the same. Fig. 10 is a plan of a filler strip blank of a slightly modified construction. Fig. 11 is a similar view of this

blank, showing its condition after the second operation has been performed thereon. Fig. 12 is a sectional view on line 12—12 of Fig. 11. Fig. 13 is an edge view 60 of the device shown in Fig. 11. Fig. 14 is an elevation of the filler strip after the third operation has been performed thereon; and Fig. 15 is a similar view of the filler strip after the final operation of closing all the 65 seams thereof has been accomplished and the filler is ready for insertion into a core-unit. Fig. 16 is an end view of the same.

Like parts are designated by the same characters and symbols of reference in all 70 the various figures.

As illustrated in Figs. 2 and 3, this radiator core comprises a multiplicity of like units A, A_a, Ab, etc., arranged side by side, and of a height and width corresponding to that of a casing in which the core is to be installed, the depth of the core varying from two to five inches according to the capacity required.

Each core unit is preferably formed of 80 two strips or ribbons of very thin sheet metal, of about #32 B. & S. gage, each strip 12, having flat longitudinal margins 14, and then longitudinal offsets as at 13, the space between these offsets being undulated by a 85 series of corrugations 15, the corrugations being, preferably, of curved formation, and these corrugations are flattened at their ends where they join the offsets, as at 16. The object of thus flattening the corrugations is 90 to prevent straining and possibly a rupture of the metal in forming these corrugations.

The ends of these strips are left blank or flat, as shown at 17, and these blank portions are bent at right angles, as at 18; and 91 a pair of these strips are then overlapped or seamed at their terminals, as at 19, so that the corrugations face each other as illustrated in Figs. 2 and 3. These core-units are placed side by side, the backs of 1 one unit facing the backs of adjacent units, whereby there is formed between adjacent units a vertical through-passage 20, of a width equal to the opposing offsets in the strips, and of a length equal to the transverse distance between the offsets 13. These through passages 20 constitute the water passages, and they are straight passages so that one can look through them when examined from either end thereof, while the 1 corrugated portions afford enlargements in these passages. The object of corrugating

these strips transversely is two-fold: first, to increase the metallic cooling area, and then to afford crotches or angles 21, for the reception and retention of the heat-absorbing fillers B located between opposing walls of the water tubes.

These fillers, in the preferred embodiment of my invention, and illustrated detached in Figs. 4 to 8 inclusive, are of novel and peculiar construction. They are formed of a single strip or ribbon, 22, of sheet metal of suitable width and, preferably, long enough to reach from the top to the bottom of a unit, although a plurality of the formed fillers may be employed, if desired, in a single unit. This ribbon is first perforated by a series of equally spaced, cross-shaped openings, there being a transverse opening 23, and two shorter, longitudinal, openings 24, terminating in the transverse openings and thereby afford the cross-shaped aperture. There is between adjacent ends of the longitudinal openings 23, a portion of the strip which I prefer to refer to as a "connector"; and at the longitudinal margins of the filler strip adjacent the terminals of the transverse openings 23, there are portions of the strip which I term "lands" 26, in order to recognize these portions in the completed filler. This strip is transversely folded or bent at right angles to the plane of the strip, as indicated by dotted lines 27, 37, in Fig. 4, and doubled upon itself centrally through the lands 26, to afford right-angular projections on the filler, as illustrated in Fig. 6. These projections are comprised of the portions of the filler strip above the transverse openings 26 and the dotted line 27, as indicated by the reference-numeral 38, and below the transverse opening 26 and the lower dotted line 27, and marked 39. These projections are at this time open at their backs, or in other words, their walls are not in contact, which I find desirable to enable this operation of folding being performed by suitable machinery. In this condition, the strip is then longitudinally folded upon itself, as illustrated by the dotted lines 28, Figs. 4, 5, 10, and 11, whereby the portions 25 form the connection between the doubled up strips, which now comprise two sections, the projections at the right of the strip shown in Fig. 5 extending from the right of the longitudinally doubled up strip in Fig. 7, while those projections at the left of Fig. 5, extend from the left of Fig. 7, the extensions being in right-angled alinement. In this condition the joints of the filler strip are still open, as heretofore mentioned, and to complete the filler, the strip is placed into a suitable die wherein first the lands 26 are forced upon each other, and then the connectors 25 pressed together so that the adjacent portions of the filler strip are now in close contact one with the other, as shown in Fig. 2. A filler, when thus completed is easily and conveniently handled, and when placed into a core-unit, the terminals of the right-angledly extending portions thereof engage the 70 crotches 21 between the corrugations of the unit strips, as illustrated in Figs. 2 and 3.

An inspection of Fig. 8 will now disclose the fact that the lands 26 extend somewhat beyond the marginal edges 29, formed by 75 the openings 23, in the filler strip, whereby shoulders 30, are formed so that when the filled is placed into the core-unit, the longitudinal margins of the filler strip are flush with the longitudinal margins of the unit- 80 strip, the portions 26 occupying the spaces 14; the shoulders 30 abutting against the offsets 13, and the portions 29 engaging the crotches 21 between the corrugations 15.

As shown in Fig. 3, there are employed 85 two complete fillers C, in each core-unit, one being pushed into the space between opposing unit walls from the front, and the other from the back of the core-unit. When in this position, the appearance of the core in 90 front and at the back is that of a rectangular cellular structure, as shown in Fig. 2, the marginal lines of the unit and the central portion of the filler forming the vertical, and the lateral projections of the filler, 95 forming the horizontal boundaries of the square cellular formation.

The spaces between the vertical walls of the core-units form air-passage C, through which air is drawn to contact with the 100 metallic surfaces of the core-units, thereby abstracting heat from these walls to reduce the temperature of the water passing through the water tubes in a downward direction; and this cooling process is augmented by the metallic fillers in the air 105 passages, the margins of which contact with the walls of the water tubes.

A core, when fully assembled, is dipped, first with its front, into a bath of molten 110 solder for a depth of about one-eighth of an inch, which solder, when congealed and hardened, will homogeneously unite the parts; and this dipping process is then repeated at the back of the core, as well as at 115 its top and bottom surfaces.

I have hereinbefore described the preferred embodiment of my invention, as disclosed in Figs. 1 to 9 inclusive, and in Figs. 10 to 16 inclusive, I have illustrated a 120 slightly modified form of the filler. In this modified construction, the metallic strip or ribbon 22, while of the same length, width, and thickness as the one shown in Figs. 4 and 5, differs therefrom in that there are 125 two alined openings 23^a, Figs. 10 and 11, which cut through the longitudinal margins of the ribbon and stop short of, or terminate at some distance from the vertical central lines 28, of this ribbon, and that longitudi- 130

nally alined slots 24^a, are provided in the strip, the length of which is, however, equal to the distance from end to end of the elements 24, Fig. 4, so as to leave between the 5 ends of the longitudinal slots 24^a, the connection 25, while the lands 26^a, are adjacent the longitudinal slots 24^a. This strip is folded in precisely the same manner as the strip shown in Figs. 4 and 5, the only difference 10 in the appearance of this filler when inserted into the core-unit being that while in the preferred embodiment of my invention the roll 25 shown in Figs. 8 and 9, is at the back of the filler, this roll 25, in the 15 modified form of construction is at the front of the core, as shown in Figs. 15 and 16, at 25^a. This modified form of construction is to all intents and purposes as effective as the preferred construction; the only reason 20 for selecting this latter construction being, that the filler has a somewhat neater appearance.

Having thus fully described this invention, I claim as new and desire to secure to 25 myself by Letters Patent of the United States—

1. In a radiator for motor vehicles having a series of vertically disposed, spaced apart, water tubes, the walls of which are 30 transversely corrugated to afford crotches or angles, a filler between adjacent water tubes, said filler comprising a metallic ribbon, there being in said ribbon a series of openings transversely disposed therein, and 35 a series of longitudinal openings, said ribbon being bent and rebent to afford vertical bars and right-angular, alined, projections, said projections extending horizontally in opposite directions from said bars, the 40 terminals of said projections being constructed to engage the crotches in the walls of the water tubes.

2. A filler for the core-units of a motor vehicle radiator, said filler being constructed 45 of a thin, sheet-metal, ribbon, there being in said ribbon spaced apart, cross-shaped openings, the main portions of said openings being transversely disposed, the branches of 50 said openings being longitudinally disposed in the longitudinal center line of said ribbon to afford lands between the margins of said ribbon and the transverse openings therein, and connectors between the terminals of the longitudinal openings, said ribbon 55 being bent and rebent to afford vertically disposed bars and right-angular projections at opposing sides of the vertical bars, said projections being axially alined,

the vertical and the hoizontal members of the filler comprising two thicknesses of the 60 metallic ribbon in intimate contact with each other.

3. A filler for the core units of a motor vehicle radiator, said filler being constructed of a thin, sheet-metal, ribbon, there being 65 in said ribbon spaced apart, cross-shaped, openings, the main portion of said openings being transversely disposed, the branches of said openings being longitudinally disposed, said longitudinal branches being in 70 the longitudinal center line of said ribbon to afford lands between the margins of said ribbon and the terminals of the transverse openings, and connectors between the terminals of the longitudinal openings, said ribbon being bent and rebent to afford vertical 75 bars, and horizontal bars at both sides of said vertical bars, said horizontal bars being axially alined, said horizontal bars being widest at their outer ends to afford 80 shoulders therein.

4. The method of producing radiator fillers for the air conduits therein, which consists in producing in a sheet-metal ribbon a series of spaced apart, cross-shaped openings, then doubling the ribbon through the transverse portions of said openings to U-shaped form and at the same time bending the ribbon at right angles adjacent the outer terminals of the longitudinal branches of 90 said openings, then doubling the ribbon longitudinally upon itself to afford right-angular, open, projections thereon, then closing these projections, and finally closing the longitudinal fold in said ribbon to force all of 95 the adjacent members of the ribbon into intimate contact with each other.

5. A blank adapted for being formed into a filler for use between water tubes of radiator cores, said blank comprising a sheet 100 metal ribbon, said ribbon having a width corresponding to the depth of a radiator core, said filler strip having a series of cross-shaped perforations in spaced apart relationship, the principal limbs of said cross-shaped perforations being transversely disposed, and the branches of the cross shaped perforations being longitudinally disposed, said ribbon being adapted for bending and rebending and doubling up longitudinally 105 to afford a filler between the water tubes of said core.

In testimony that I claim the foregoing as my invention, I have hereunto set my hand.

PHILMORE F. SPERY.
